UNITED STATES PATENT OFFICE.

HAROLD B. MADDER, OF SHARON, PENNSYLVANIA, ASSIGNOR TO NATIONAL MALLEABLE AND STEEL CASTINGS COMPANY, OF CLEVELAND, OHIO, A CORPORATION OF OHIO.

SHOCK-ABSORBING MECHANISM.

Application filed January 6, 1926. Serial No. 79,604.

Fig. 1 is a plan, partly in section, of a shock absorbing mechanism embodying my invention; Fig. 2 is an end elevation of the gear with the front follower removed; and 5 Figs. 3, 4 and 5 are details of the releasing plunger.

My invention relates to shock absorbing mechanism, and particularly to friction draft gears for railway vehicles of the type described in Letters Patent 1,192,571 of Ernest H. Schmidt, granted July 26, 1916, and 10 1,301,809 of Chester K. Brooks and Ernest H. Schmidt, granted April 29, 1919. My invention in particular comprises means for 15 effecting the release of the follower wedge and friction shoes and the various features which I shall hereinafter describe and claim.

Referring to the drawings, the central friction member 2 has longitudinally extending, outwardly radiating arms 3, and terminates at its rear end in an enlarged base 4. Between the outwardly radiating arms 3 are the friction shoes 5, which engage the longitudinally extending friction faces of 25 such arms 3. Each friction shoe has a wedging surface 6 engaged by a wedge surface 7 on the front follower 8, and a rear surface 9 against which an intermediate follower 10 bears. Between the intermediate 30 follower 10 and the base 4, are a plurality of spring elements 11 (one for each shoe), which I have shown in the form of nested springs.

For the purpose of assisting in release, I 35 have provided a plurality of plungers 12, which move with the wedge 8, may be made integral therewith, and seat in apertures 14 in the intermediate follower 10. The rear end of each plunger 12 extends beyond the 40 rear surface of the intermediate follower, and is engaged by the forward ends of the coils of a spring element 11, so that a spring element 11 where it is engaged by plunger 12 is held out of engagement with the intermediate follower, while the parts of the coils 45 of the spring element diametrically opposite bear upon the intermediate follower. The rear ends of the plungers are slightly bevelled so that the springs bear against the 50 plungers only in the area indicated at α (Fig. 4), thus giving the coils of the springs opportunity to equalize their pressure between the plunger and the intermediate follower.

After compression of the gear, it will be 55 seen that as each plunger 12 extends a slight

distance beyond the rear face of the intermediate follower each plunger will receive a substantial proportion of the compressive force of the spring element 11 with which it is engaged, and that the plungers 12 will accordingly force the wedge follower 8 forwardly independent of the intermediate follower 10 and the shoes 5, thus breaking the adhesion between the wedge and shoes. Then, as the plungers 12 are forced by the 60 springs forwardly through the intermediate follower, the spring element will come into full bearing with the intermediate follower 10, and the full force of the springs will be exerted thereon, and through the follower 70 upon the shoes, thus breaking the adhesion of the shoes to the central friction member.

Draft gears constructed in accordance with my invention have proved very efficient in service and have eliminated the sticking 75 of the parts during release, without affecting the capacity of the gears when under compression.

The terms and expressions which I have employed are used as terms of description 80 and not of limitation, and I have no intention, in the use of such terms and expressions, of excluding any mechanical equivalents of the features shown and described, or portions thereof, but recognize that various 85 structural modifications are possible within the scope of the invention claimed.

What I claim is:

1. In frictional shock absorbing mechanism, a longitudinally-extending included friction member having a plurality of diverging longitudinally extending friction faces; a friction shoe engaging each of such faces; each shoe having an inclined wedging face; a wedge member engaging the wedging face of each shoe; a compression spring arranged in tandem with each shoe; a plunger having bearings on the wedge and on the spring, the spring as the pressure abates being arranged to exert direct pressure on one 90 side on the wedge through the plunger and on the other side on the shoe, and thereby cause release of the wedge from the shoe and the shoe from the included member.

2. In frictional shock absorbing mechanism, a longitudinally-extending included friction member having a plurality of diverging longitudinally extending friction faces; a friction shoe engaging each of such faces; each shoe having an inclined wedging 100 105 110

face; a wedge member engaging the wedging face of each shoe; a compression spring arranged in tandem with each shoe; an intermediate follower between shoe and spring disposed so as to transmit pressure from one to the other; and a plunger having bearings on the wedge and spring and seating in an aperture of said follower, said plunger when said compression abates being arranged under impulse of the spring to move the wedge independently of the follower or shoe.

3. In frictional shock absorbing mechanism, a longitudinally-extending included friction member having a plurality of diverging longitudinally extending friction faces; a friction shoe engaging each of such faces; each shoe having an inclined wedging face; a wedge member engaging the wedging face of each shoe; a compression spring arranged in tandem with each shoe; an intermediate follower between shoe and spring disposed so as to transmit pressure from one to the other; and a plunger bearing on the wedge, seating in an aperture in the follower and projecting to the rear of the follower, the spring being normally tilted by having on one side a bearing on the follower and on the other a bearing on the plunger, whereby when the pressure abates the spring causes the wedge to release from the shoe and then the shoe to release from the included member.

4. In frictional shock absorbing mechanism, a longitudinally-extending included friction member having a plurality of diverg-

ing longitudinally extending friction faces; a friction shoe engaging each of such faces; each shoe having an inclined wedging face; a wedge member engaging the wedging face of each shoe; a compression spring arranged in tandem with each shoe; an intermediate follower between shoe and spring disposed so as to transmit pressure from one to the other; and means supported in and movable relative to the intermediate follower for transmitting pressure from spring to wedge; said spring being adapted to resist severally the inward movement of the wedge and shoe during compression and to cause the several release of wedge and shoe when the pressure abates.

5. In frictional shock absorbing mechanism, a longitudinally-extending friction member; friction shoes engaging said member, each shoe having an inclined wedging face; a wedge member engaging the wedging face of each shoe; a compression spring arranged in tandem with each shoe; an intermediate follower between shoe and spring disposed so as to transmit pressure from one to the other; and means supported in and movable relative to the intermediate follower for transmitting pressure from spring to wedge; said spring being adapted to resist severally the inward movement of the wedge and shoe during compression and to cause the several release of wedge and shoe when the pressure abates.

HAROLD B. MADDER.
